UNITED STATES PATENT OFFICE.

WILLIAM MONROE WHITE, OF MILWAUKEE, WISCONSIN.

CENTRIFUGAL PUMP.

1,134,655.

Specification of Letters Patent.

Patented Apr. 6, 1915.

Application filed May 1, 1913. Serial No. 765,401.

To all whom it may concern:

Be it known that I, WILLIAM MONROE WHITE, a citizen of the United States, residing at Milwaukee, in the county of Milwaukee and State of Wisconsin, have invented a certain new and useful Improvement in Centrifugal Pumps, of which the following is a specification.

This invention relates to improvements in the construction of centrifugal pumps, blowers, or similar devices, and particularly to improvements in the construction of the casings and supporting frames for such devices.

An object of the invention is to provide an inclosing casing and supporting frames for centrifugal pumps and like apparatus, which is simple in construction and in which the number of different parts comprising the structure is reduced to a minimum.

Another object is to provide a pump casing in which some of the parts may be readily interchanged with others.

Still another object is to provide a pump casing in which the direction of the inlet and discharge passages leading to the pump casing may be readily varied to suit different conditions.

A further object of the invention is to provide a simple and effective supporting frame for the pump casings and the bearings in which the rotary pump elements are mounted, whereby the bearings may be constantly maintained in a fixed position irrespective of the adjusted positions of the casings.

A particular object is to provide an upper rib connecting each bearing to the spiral casing.

A clear conception of several embodiments of the invention may be had by referring to the drawing accompanying and forming a part of this specification in which like reference characters designate the same or similar parts in the various views.

Figure 1 is a front view of a centrifugal pump, partly in section. Fig. 2 is an end view of a centrifugal pump showing the casing supporting frame, and showing one of the suction inlet passages and the pump casing in an angularly adjusted position in dot and dash lines. Fig. 3 is a front view of a modified form of pump supporting frame.

The centrifugal pump consists essentially of a spiral pump casing 1 having suction 55 passages 7 leading thereto and a discharge passage 6 leading therefrom, and having a pump rotor 8 rotatable therein. The suction inlet passages 7 are formed in the interchangeable suction heads 2 which connect 60 with the suction openings leading to the rotor 8 through passages formed in the end covers 10. The interchangeable spider supporting frames 3 each consist of a circular flange 90 connected with a bearing housing 4 by means of a plurality of spaced ribs and supported upon suitable frame supporting feet or pads 18. The pump shaft 5 which carries the pump rotor or runner 8, is mounted in bushing bearings 14 secured 70 within the bearing housings 4 by means of locking screws 15. Ring oilers 13 which are admitted to the bearing housings 4 through openings which are normally inclosed by means of bearing caps 16, serve to provide 75 sufficient lubrication to the bearings 14. The shaft 5 passes directly through the suction inlet casings 2, the joints between the shaft 5 and the casings 2 being packed by means of suitable stuffing boxes 12. 80

The suction pipes 17 connect with the suction inlet passages 7 of the suction heads 2, and serve to admit the fluid to the pump runner 8 from the supply source. The discharge pipe 19 connects directly with the 85 pump discharge passage 6 of the casing 1.

The casing 1, end covers 10, and supporting frames 3 are united by means of circular series of equally spaced studs 9 which are secured to the circular lugs 11 of the casing 90 1 and have outer ends extending through registering openings in the end covers 10 and circular flanges 90 of the supporting frames 3. The studs 9, it is evident, are not essentially such, as bolts may be readily 95 used as an alternative means of uniting the elements without involving additional invention. The surfaces of coaction of the casing 1, end covers 10 and frames 3 with each other are plane surfaces perpendicular 100 to the axis of the shaft 5.

The casing 1 is formed symmetrical about a plane passing through the center thereof and perpendicular to the axis of the shaft 5. The end covers 10 and suction chambers 2 105 which are formed in one therewith, are exact

duplicates, being drilled in a like manner, thus making them interchangeable. The spider supporting frames 3 are likewise constructed and drilled exactly alike, thus also 5 making them interchangeable. The casing 1 and the end covers 10 are adjustable to various angular positions relative to the spider frames 3, thus permitting disposition of the inlet pipes 17 and discharge pipe 19 10 in various directions, without changing the position of the bearing casings 4. Angular adjustment of the casing 1 may be accomplished by removing the clamping nuts from the studs 9 and shifting the end covers 10 15 and spider frames 3 along the shaft 5 and away from the casing 1 until the studs 9 are withdrawn from the openings in the end covers 10 and frames 3, after which the casing may be shifted to the desired angular 20 position and the elements reassembled. If it is desired to adjust the end covers 10 through angles which are greater than the spacing of the adjacent spider ribs of the frames 3 will permit, it is necessary to remove the end covers 10 and suction heads 2 25 from within the frames 3 and to reassemble the elements so that the desired angular positions may be attained.

In the form of spider supporting frame 30 disclosed in Fig. 3, the frame is formed of two portions, namely, an upper portion 23 and a lower portion 26. These frame portions 23, 26, have semi-circular flange portions 27, 30, which with the frame portions 35 23, 26, assembled, are secured to each other by means of bolts 28 or other suitable clamping devices. The bearing housing cap 24 is formed in one with the upper frame portion 23 and with the frame portions 23, 26, 40 assembled, is clamped to the lower bearing portion 31 by means of bolts 25 or other suitable clamping means. The lower frame portion 26 is provided with suitable supporting feet or pads 29. The application of 45 the modified form of supporting frame to an assembled pump is analogous to that of the spider supporting frames 3, as disclosed in Figs. 1 and 2. The angular adjustments of the respective elements with 50 the use of the modified frame, are also attained in the manner above explained.

It will be noted that by making the various parts on either side of the pump interchangeable, the number of stock parts required by manufacturers of these pumps is 55 reduced to a minimum, since the number of different parts comprising a complete pump housing and supporting frame is only three, these being the casing 1, the end covers 10, 60 and the spider supporting frames 3. The similar spacing of the clamping devices or studs 9 on opposite sides of the casing 1, and the symmetrical formation of this casing, readily permits reversal of this casing and

also permits angular adjusting of the casing 1 and the end covers 10 to various positions relative to the supporting frames.

The split supporting frame disclosed in Fig. 3 avoids the use of a pressed-in bushing bearing 14 as disclosed in Fig. 1. This 70 structure, however, increases the number of parts required to make up the frame and also requires additional machining of the parts along the frame parting surfaces.

It should be understood that it is not desired to be limited to the exact details of construction shown and described, for obvious modifications will occur to a person skilled in the art.

It is claimed and desired to secure by 80 Letters Patent,—

1. In a centrifugal pump, a casing, an end cover in direct engagement with each side of said casing, each of said end covers forming a suction passage to said casing, a detachable frame in direct engagement with each of said end covers, and common means on each side of said casing for connecting said casing with one set of end covers and frames. 90

2. In a centrifugal pump, a casing, an end cover in direct engagement with each side of said casing, each of said end covers forming a suction passage to said casing, a detachable frame in direct engagement with each of said end covers, and common means on each side of said casing for connecting said casing with one set of end covers and frames in various relative angular positions. 95

3. In a centrifugal pump, a casing, an end cover in direct engagement with each side of said casing, each of said end covers forming a suction passage to said casing, a detachable frame in direct engagement with each of said end covers for supporting said casing, and a series of equally spaced clamping devices on each side of said casing for connecting said casing with one set of end covers and frames. 100

4. In a centrifugal pump, a casing forming a discharge passage, an end cover forming a suction passage, a frame having supporting pads, and a series of equally spaced clamping devices for uniting said casing, 105 end cover and frame in various relative angular positions. 110

5. In a centrifugal pump, a casing formed symmetrical about a plane, interchangeable end covers coacting directly with said casing 120 and forming closures therefor, and interchangeable supporting frames coacting directly with said covers, both said end covers and said frames being secured to said casing on opposite sides of said plane of symmetry. 125

6. In a centrifugal pump, a casing, rotary elements within said casing, bearings for said rotary elements, spider frames con-

necting said bearings and said casing and
having supporting pads for the pump, and
a suction inlet pipe extending to said cas-
ing between successive arms of said spider
5 frames.

In testimony whereof, the signature of the

inventor is affixed hereto in the presence of
two witnesses.
